SHIP'S HOLD STANCHION ASSEMBLY

Samuel M. Rosamond and John C. Campbell, New Orleans, La., assignors to Boland Machine & Manufacturing Company, Inc., New Orleans, La.

Application June 29, 1951, Serial No. 234,188

1 Claim. (Cl. 114—78)

This invention relates to cargo carrying vessels particularly of the type carrying grain and similar products and wherein it is necessary to change the arrangement of the partitions or stanchions to accommodate different types of cargo, and in particular this invention includes a plurality of preformed structural shapes having channels in the sides designed to be vertically positioned between the decks and in the hold of a ship whereby permanent grooves or tracks are provided for holding the ends of planks or boards forming bulkheads or retaining partition in the ship.

The purpose of this invention is to provide supporting elements between the decks and in the hold of a ship whereby materials of which the partitions or walls are formed may be readily installed and also readily removed.

The conventional method of dividing the areas between bulkheads between the decks and in the hold of a ship dividing walls and partitions are constructed as required and when it is desired to use the ship for different cargo the walls and partitions are constructed as required and when it is desired to use the ship for different cargo the walls and partitions are removed and discarded. Considering the present cost of material and labor this process is very costly. With this thought in mind this invention contemplates an improved method of forming stanchions in the hatches, between the decks and in the hold of a ship whereby steel supporting stanchions or posts are permanently installed and whereby these structural shapes are designed to receive ends of temporary wall forming elements such as boards and wherein when it is desired to use a ship for cargo of a different type the boards may readily be removed without disturbing the structural shapes forming the stanchions, posts, and the like.

The object of this invention is, therefore, to provide means for converting conventional columns and other supporting elements between the decks and in the hold of a ship whereby channels are provided in different sides of the elements for temporarily retaining ends of wall forming members.

Another object of the invention is to provide an improved method of forming grain carrying bins between bulkheads between decks and in the hold of a ship whereby greater quantities of bulk grain may be stored and carried therein.

A further object of the invention is to provide an improved method of forming dividing walls and partitions between the decks and in the hold of a ship whereby wall forming elements may be readily removed and replaced without damaging the supporting members.

A still further object of the invention is to provide an improved method of dividing the hatches, the areas between the decks, particularly between the bulkheads and also in a hold of a ship whereby the cargo carrying areas of a ship are readily convertible to carrying different types of cargo wherein the dividing elements are of comparatively simple and economical construction.

With these and other objects and advantages in view the invention embodies a plurality of structural shapes partic-

2

ularly of H and channel formations whereby the shapes are adapted to receive the ends of boards or other material of which partitions are formed.

Other features and advantages of the invention will appear from the following description taken in connection with the drawings wherein:

Figure 1 is a longitudinal section through part of the hull of a ship with parts broken away illustrating a typical arrangement of the stanchions therein.

Figure 2 is a sectional plan through the section of the ship shown in Figure 1 taken on line 2—2 thereof illustrating a typical arrangement of different types of stanchions and supporting elements.

Figure 3 is a cross section through a simple form of stanchion wherein the parts are positioned to form an H-beam.

Figure 4 is a similar section showing flanges at one side of the beam shown in Figure 3 whereby a channel is provided on the side of the beam.

Figure 5 is a section through a typical H column or beam with flanges welded to the web thereof whereby forming channels on opposite sides of the beam.

Figure 6 is a section similar to that shown in Figure 4 illustrating a similar channel positioned on the opposite side of the H beam shown in Figure 3.

Figure 7 is a section through stanchion of a different type, showing a pair of right angular positioned channels therein.

Figure 8 is a view showing a similar shape with an additional channel positioned on one side.

Figure 9 is a view showing a shape similar to that shown in Figure 4 with the side channel positioned at one end of the shape.

Figure 10 is a detail illustrating a conventional form of channel which provides a stanchion particularly adapted to be positioned against a wall.

Figure 11 is a detail illustrating a stay bolt or support connecting a center partition to the side wall of a ship and showing a turn buckle therein.

Figure 12 is a detail showing a section taken on line 12—12 of Figure 11.

Figure 13 is a detail showing the inner side of the stanchion shown in Figure 11 showing a U or eye welded to the side of a post or stanchion.

Figure 14 is a detail showing sections through horizontally disposed beams showing a modification and illustrating a method of bridging across two beams for supporting stanchions positioned above and below the beams.

Figure 15 is a modification showing a typical detail illustrating a connection between the lower end of a stanchion and a channel positioned upon the top of a tank.

Figure 16 is a side elevational view of the detail shown in Figure 15.

Figure 17 is a side elevational view of a typical stanchion adapted to extend between a top of a tank and a deck above.

Figure 18 is a side elevational view of the detail shown in Figure 17.

Figure 19 is a detail showing a modification wherein clip angles on the end of a channel on beam are connected by lag screws to a deck.

Figure 20 is a detail illustrating the application of the shape shown in Figure 7 to a beam and brow plate.

Figure 21 is a section showing a side view of the connection shown in Figure 20 being taken on line 21—21 thereof.

Figure 22 is a detail showing a connection between a channel or beam and a girder.

Figure 23 is a detail showing a side view of the connection shown in the Figure 22.

Figure 24 is a sectional plan illustrating a connection including the shape shown in Figure 4 as connecting two

sections of a partition with another partition extended at a right angle to the connection.

Figure 25 is a section through a beam or girder upon which the stanchion shown in Figures 4 and 24 is mounted.

Figure 26 is a detail illustrating a modification of a connection between the end of beam or hatch strong back and a stanchion.

Figure 27 is a detail showing a section taken on line 27-27 on Figure 26 showing a side view of the connection shown therein.

Figure 28 is a detail showing a modification of a connection between the upper end of a post or stanchion and a horizontal beam.

Figure 29 shows a side view of the connection shown in Figure 28.

Figure 30 is a detail showing a clip angle for mounting a beam or hatch strong back on a stanchion.

Figure 31 is a side view of the connection shown in the Figure 30.

Figure 32 is a modification illustrating a different connection between a girder and a supporting member or stanchion.

Referring now to the drawings wherein like reference characters denote corresponding parts the improved ship's stanchions of this invention includes uprights, posts, or stanchions formed with different structural shapes with 25 boards forming dividing walls and partitions which are removably mounted in and supported by the shapes.

As illustrated in the drawings stanchions or posts are permanently installed between the decks and in the hold 30 of the ship and the planks or boards 10 are freely positioned in channels in the sides of the stanchions, and when it is desired to use the ship for a different cargo the boards are readily removed, and these boards and stanchions may be removed and replaced as many times as 35 may be desired.

As illustrated in Figure 5 the main stanchions of the dividing walls are formed by welding plates 17 and 18 on a web 19 of an H beam 20 with corresponding plates 21 and 22 on the opposite side whereby open channels 23 40 and 24 are provided for holding the ends of the boards 10.

Intermediate stanchions are formed with H shapes 25 having flanges 28 and 29 extended from the flange on the opposite side whereby channels for cross partitions are provided with open channels 30 and 31 extended in one 45 direction and 32 and 33, in the other direction.

Similar stanchions are provided, at the ends with H beams 34, as shown in Figure 4 provided with spaced flanges 35 and 36 that extend from the flange on one side of the shape and this provides open channels 37 and 38 in the shape 34 and a channel 39 extended at one side thereof.

At spaced points in the center partitions a stanchion formed with an H beam 40, as illustrated in Figure 3, and in this open channels 41 and 42 are provided for receiving ends of the boards 10.

As is also shown in Figure 2, the bin is provided with corner stanchions, as illustrated in Figure 7, wherein plates 43 are provided with flanges 44 and 45 and a flange 46, extended from the outer edge of the flange 45 provides an open channel 47 at one side of the shape. A similar channel 48 for holding boards extended at a right angle to the boards in the open channel 47, is provided between the flanges 44 and 45.

A stanchion for connecting an end wall of a bin to a continuous partition is illustrated in Figure 9, wherein an H beam 49 is provided with side flanges 50 and 51 thereby providing channels 52 and 53 and a channel 54 on one side thereof.

A different type of corner stanchion is illustrated in Figure 8 wherein a plate 55 is provided with flanges 56 and 57 and additional flanges 58 and 59 are formed on the edges of the flanges 56 and 57 whereby the shape is provided with a center channel 60 and side channels 61 and 62.

Partitions or walls extended from the side of the bins are held by stanchions, as illustrated in Figure 10, wherein in a web 63 with flanges 64 and 65 extended therefrom provides a channel shaped member with an open channel 66 therein for receiving the ends of the boards.

As illustrated in Figure 11 some of the shapes may be provided with U-shaped members or eyes 67 and stay wires 68 connected to the eyes by clevises 69 are connected to webs 70 at the opposite side of the bin or on the wall of the ship with turnbuckles 71 connected to eyes 72 on the web 70 to the ends of the wires 68.

As illustrated in Figure 2 the center partition may also be supported from the sides of the ship by the guy wires or stay rods 68, and similar stay bolts or wires may be 15 provided for supporting the sides of the bins wherein cables 73 and 74 connected by turnbuckles 75 are attached to eyes 76 similar to the eyes 67 and 72 on the stanchions.

Figures 14 to 32 illustrate different forms of structural connections used in mounting the stanchions in ships, wherein, as illustrated in Fig. 14, the upper end of a stanchion 77 is positioned between horizontally disposed beams 78 and 79 and in this type of connection the upper end of the stanchion 77 is connected to an angle iron 80 by bolts 81. By the same means stanchion 82 extended upwardly from the deck of the ship is attached by bolts 83 to an angle 84 which is secured to the beams 85 and 78.

Figures 15 and 16 show a stanchion 86 mounted on a horizontally disposed channel 87 with clip angles 88 and 89, the clip angles being secured to the stanchion, preferably by welding. The flanges of the channel 87 are cut away to provide an opening 90 to which access is provided to nuts and bolts 91 connecting the clip angles to the channel.

Figures 17 and 18 show a stanchion 91 connected to the under surface of a deck 92 with clip angles 93 and 94 and, as illustrated, the lower end of the stanchion is connected to the upper surface of a tank 95 by clip angles 96 and 97.

Figure 19 shows a stanchion 98 attached to frame flooring or a deck 99 with a screw 100 extended through clip angles 101.

Figure 20 is a sectional plan, showing a shape, as illustrated in Fig. 7, positioned on a cross beam or strongback 102 with the stanchion secured to the girder by bolts 103 which extend through plate 104. This figure and also Figure 21 show the stanchion fitted into the brow plate 104 at the strongback of the hatch.

Figures 22 and 23 show additional connections to a hatch strongback wherein a stanchion 106 is connected by clip angles 107 and 108 to a strongback or girder 109.

Figures 24 and 25 show a stanchion 34 as illustrated in Figure 4, mounted on the upper flange of a girder 110 with a base plate 111 and bolts 112.

Figure 26 illustrates an alternate method of longitudinal hatch girder or strongback 113 to a stanchion 114, the girder being connected to the stanchion by clip angles 115 at the sides and 116 at the outer edge.

Figures 28 and 29 show further modifications wherein stanchions support deck beams and longitudinal girders and a deck beam 117 positioned on the upper end of a stanchion 118 is secured in position by means of a top plate 119 and clip angles 120 and 121, the clip angles being secured to the top plate by bolts 122.

Figures 30, 31 and 32 show a hatch strongback 128 positioned on a stanchion 129 with the stanchion secured into position with the clip angles 130 and 131 which are secured to the stanchion, preferably by welding, and to the strongback by bolts 132. In Fig. 32 a web 133, positioned between clip angles 134 and 135 is secured by bolts 136 to a top plate 137 which is welded on a stanchion 138.

It will be understood that these connections are only typical as the parts may be attached to a strongback of a hatch, the walls of a ship, and to permanent framing in the ship by other suitable means.

As illustrated in Figure 2 stanchions are installed in different positions in relation to the hatches, tanks, and other parts of the vessel, and also the dividing walls and partitions will be re-inforced and braced by suitable means.

The stay bolt or cable 68 with the turnbuckle therein, as illustrated in Figure 2, is used for bracing stanchions in the side walls of the bins and it will be understood that the eyes 67 are attached, preferably by welding, to side flanges of stanchions as indicated by the numeral 40 so that the guy wires, at cables or rods are attached to the stanchions at different points throughout the installation. Also, as illustrated in Fig. 13, the upper ends of the stanchions may be connected by clip angles 141 to deck plates 142, or other elements.

The stanchions may, therefore, be installed in the hatch between the decks, and the hold of a ship and as grain is dumped through the hatch 14 as shown in Fig. 1, the grain will flow into the different compartments of the bin and will also flow laterally to areas 143 and 144 between the decks.

With the stanchions and other framework in position the boards are installed with the ends extended into open channels of the stanchions, as illustrated in Figures 3 to 10 whereby dividing walls and partitions are provided to form bins throughout the hull of the ship.

As illustrated in Figure 1 the boards 10 are placed between the upper parts of the stanchions whereby open areas are provided below the boards. The stanchions are provided with stops such as bolts 145 which may be extended through the flanges, so that the grain is free to flow below the dividing walls at the sides and into open areas in the hold.

It will be understood that the arrangement of dividing walls and partitions for the supporting stanchions, particularly as illustrated in Fig. 2, is only typical, as different arrangements of the parts are required for each section of

the ship between the bulkheads, and the stanchions and boards may be re-grouped to form bins of different shapes and sizes.

It will be understood that modifications may be made in the design arrangement of the parts without departing from the spirit of the invention.

What is claimed is:

In a ship having walls and a bottom defining a hold, a plurality of removable planks, a plurality of main stanchions including an H-beam embodying a web in said hold, plates secured to said web and defining open channels for holding the ends of said planks, intermediate and end stanchions of H-shape having flanges defining open channels, corner stanchions having plates and flanges providing open channels, certain of said planks on the corner stanchions providing bins, stay wires having eyes and flexible tension members including means thereon for adjusting the length thereof extending between the stanchions and the walls of the ship, said planks being placed between upper parts of the stanchions whereby open areas are provided below the planks, and removable means secured to the stanchions and restraining the planks above the bottom of the ship whereby passageways therebelow are provided and whereby the planks can be temporarily restrained from dropping.
